UNITED STATES PATENT OFFICE.

CLARENCE V. COURTRIGHT, OF MIAMI, FLORIDA.

BED-PAN.

1,171,094.

Specification of Letters Patent.

Patented Feb. 8, 1916.

Application filed June 17, 1915. Serial No. 34,734.

To all whom it may concern:

Be it known that I, CLARENCE V. COURTRIGHT, a citizen of the United States, residing at Miami, in the county of Dade, State 5 of Florida, have invented certain new and useful Improvements in Bed-Pans; and I do hereby declare the following to be a full, clear, and exact description of the invention, such as will enable others skilled in the 10 art to which it appertains to make and use the same.

This invention relates to improvements in hospital appliances and particularly to bed pans.

15 One object of the invention is to provide a device of this character which is efficient in use to protect both the patient and the bed.

Another object is to provide a device of 20 this character which is of such construction that the same can be quickly and conveniently placed in position for use without any inconvenience to the patient, the device being used in connection with a mattress 25 having a removable plug to provide an opening for introduction of the receptacle.

Another object is to provide a bed pan of such construction that the same can be easily emptied.

30 Other objects and advantages will be apparent from the following description when taken in connection with the accompanying drawing.

In the drawing: Figure 1 is a side elevation of my improved bed pan showing the 35 same applied to a mattress, the mattress being shown in section, Fig. 2 is a top plan view of the pan, Fig. 3 is a longitudinal sectional view on the line 3—3 of Fig. 2, 40 and Fig. 4 is a transverse section on the line 4—4 of Fig. 2.

Referring particularly to the accompanying drawing, 10 represents an elongated plate formed of enameled metal, porcelain 45 or other suitable material for this purpose through which is formed an opening 11.

Below this opening, and connected to the plate is a receptacle proper 12, said receptacle being of any desired shape but preferably round, and adapted to be inserted 50 through the opening 13 in the mattress 14. It will be understood that there is a plug formed of the same material as the mattress which is adapted to be fitted into this hole in the mattress, as this forms no part 55 of the invention, it is not shown.

At one side of the opening 11 and extending toward one end of the plate 10 is a downwardly and inwardly inclined and transversely concaved portion 15. On the 60 adjacent end of the plate there is an upwardly extending and longitudinally extending tunnel-like member 16 which greatly facilitates the emptying of the pan and prevents any splashing. At the opposite side 65 of the opening there is a slightly upturned flange extending approximately half way around the opening, as shown at 17, this flange acting as a guard.

A cover 18 is provided for the chamber 70 12, said cover being provided with a handle 19, and with a hook 20 for engagement in an opening 21 in the member 16.

What is claimed is:

A bed pan comprising a receptacle 75 having an upwardly and outwardly extending flange surrounding the upper side thereof, said flange being slightly elongated, one end portion of the flange having a channel extending from the receptacle to the end of 80 the flange, an upwardly extending arched wall disposed over the said channel and provided with an opening in its inner end portion, and a removable cover for the receptacle provided with a hook member for engagement in said opening. 85

In testimony whereof, I affix my signature, in the presence of two witnesses.

CLARENCE V. COURTRIGHT.

Witnesses:

CORA L. GEROCK,

JOHN W. SHISLER.
